UNITED STATES PATENT OFFICE.

ANTHONY J. METZ, OF DAVENPORT, IOWA.

INTERNAL-COMBUSTION ENGINE.

Application filed September 9, 1922. Serial No. 587,160.

To all whom it may concern:

Be it known that I, ANTHONY J. METZ, a citizen of the United States, residing at Davenport, in the county of Scott and State of Iowa, have invented certain new and useful Improvements in Internal-Combustion Engines, of which the following is a specification.

My invention pertains to improvements in internal-combustion engines, and refers more specially to a novel and efficient arrangement of the cylinder and piston. In pistons of usual construction, in the operation of the engine such pistons, and the rings thereon are subject to expansion, as a result of which the rings engage the wall of the cylinder too tightly, causing an abrasion or scoring thereof, and soon requiring to be remedied, by re-grinding the cylinder, or other means. I aim to obviate this difficulty by the use of a piston which does not contain the usual rings, and which piston is permitted a normal degree of expansion without any undue engagement with the cylinder wall.

Another purpose of the invention is to provide means for absolutely preventing the escape of any part of the explosive charge, or the gases formed therefrom, so that the full force of the explosion will be expended upon the piston.

Another purpose of the invention is to have a construction wherein a piston is used, the skirt portion of which is capable of a reciprocating movement between the cylinder wall on the outside thereof and the outer wall of a hollow cylindrical body member suspended within the cylinder, and at the inner end of which are positioned the inlet and exhaust valve, as well as the ignition devices for such cylinder. In an arrangement of this kind, wherein the valves are contained within a limited space, necessarily less than the inner diameter of the piston, it is essential that such valves shall possess the greatest amount of area possible. Otherwise the volume of hydrocarbon mixture entering the space between the piston head and inner body member will be inadequate to perform the required work, and the exhaust outlet will be insufficient to permit a proper escape of the dead gases, resulting in a back pressure of such gases, detrimental to the successful operation of the

engine. In the present invention it is sought to make use of the greatest amount of space for said purposes, which is permissible in connection with accompanying features for keeping such parts in perfect operating condition. This results in a maximum supply of explosive mixture, and corresponding amount of working force of the engine. It also insures an ample clearance of the exhaust gases following the successive explosions.

It is also essential that the intake capacity and exhaust outlet shall be commensurate with the valve area, and this is accomplished by providing intake and exhaust conduits of a novel character, and of ample capacity. While the valves occupy a position on a diametrical line of the body member, by a novel arrangement the conduits are disposed at one side of the center line, and so as to be out of the way of the valve-stem mechanism. In the formation of said conduits the wall of the central body member is utilized as one of the walls of each of said conduits, whereby the construction is greatly simplified, and all of the space within said member made use of.

Another purpose of the invention is to have all parts of the body member, including the conduit partitions and valve-stem mountings, integrally formed, so that the same can be cast or otherwise produced in a single piece. This tends to increase the cheapness of production, and makes it impossible for any of the parts to separate, so as to cause leakage of gas or water, or otherwise cause the same to become inoperative.

Another object thereof is to have the valve-stems operate in enclosed mountings, a great part of which is within reach of the cooling elements in said body member. This also prevents such parts from becoming fouled with carbon or other residuum of the explosions.

Another purpose of the invention is to provide a heat-modifying space between the intake and exhaust conduits, of a character tending to induce an upward movement of the heat-modifying elements, and assisting the radiation of the heat, more specially from the exhaust conduit.

Another object of the invention is to provide a water cooling system which will ex-

tend to all of the parts of the device which are liable to become super-heated, and prevent the same from becoming overheated.

The above mentioned, and other features 5 and advantages of the invention will more fully appear from the following specification, reference being had to the accompanying drawings, in which:

Fig. 1 is a vertical longitudinal section 10 of a cylinder equipped with the invention, on the broken line 1—1 of Fig. 4.

Fig. 2 is a similar section on the broken line 2—2 of Fig. 4.

Fig. 3 is a cross-section of the cylindrical 15 casing 11.

Fig. 4 is a plan view of the head 12.

Fig. 5 is a cross-section on the broken line 5—5 of Fig. 2.

Similar parts are indicated by corresponding 20 reference characters throughout the several figures.

The reference number 10 indicates a cylinder, within the upper part of which is enclosed a cylindrical casing 11, provided at 25 its upper end with a head 12, of rectangular form. Said head may be secured to the cylinder 10 by bolts or similar fastening means. A space is left between the wall of the cylinder 10 and the casing 11, within which 30 space is slidably the shell of a piston 13, closed at its lower end by a head 14, preferably of convexo-concave form. The head 14 is fitted with a pair of perforated ears 15, with which the end of a connecting-rod 35 16 is pivotally connected.

Within the casing 11 is a tubular mounting 17, in which is vertically movable a valve-stem 18, on the lower end of which is a valve 19, normally closing an opening 20 in the lower end of the casing 11. From 40 said opening a passage 22 extends upwardly to an intake 23 in the head 12 (Figs. 3 and 5), which intake is connected with the carburetor or other source of fuel supply 45 of the engine. The passage 22 is enclosed on two sides by walls 24 and 25, and on the opposite side by the wall of the casing 11, and at its lower end said passage is off-set 50 so that the wall of the opening 20 will be concentric with the valve stem 18. Loosely mounted on the upper end of said valve-stem is a button 26, between which and the head 12 is interposed a coiled spring 27, the 55 tendency of which is to hold the valve 19 on its valve seat. The pressure of the spring may be released by means of a lever 28, fulcrumed on a support 29 on the head 12, and adapted to be actuated in the usual manner 60 from some part of the engine mechanism, by means of a rod 30.

The casing 11 also contains a tubular mounting 32, within which is vertically movable a valve-stem 33, upon the lower end of which is fixed a valve 34, normally 65 closing an opening 35 in the lower end of

the casing 11. A passage 36 connects this opening with an exhaust outlet 37 in the head 12. The passage 36 is enclosed on two sides by walls 38 and 39, and on the opposite sides by the wall of the casing 11, and is also off-set at its lower end, so that the wall of the opening 35 will be concentric with the valve-stem 33. The valve 34 is held normally on its seat by a coiled spring 40 on the upper end of the stem 33, and said valve-stem may be manipulated by means of a rod and lever action similar to that shown for the valve-stem 18, but not set out in the drawings herein.

The casing 11 also contains a tubular member 41, in the lower end of which is seated a spark plug 42, the terminals of which project below the end of the casing, and by the sparking of which a charge is ignited in the space below said casing.

The tubular members 17, 32, and 41 and the inner walls of the passages 22 and 36 are entirely surrounded by a water space 43 (Fig. 3), which has an extension into the space 44 between the adjacent walls of said passages. At the upper end of said space is an opening 45, through which a connection can be effected with the radiator of the engine. The water space also extends downwardly to the lower end of the casing 11, surrounding the lower ends of the passages 22 and 36, and valve seats at the lower ends thereof, protecting said parts from an excessive amount of heat. The water space is also projected upwardly into the head 12, from which it communicates through openings 46 with a water jacket 47 enclosing the cylinder 10. When the engine is in operation the heating of the water in the lower part of the casing 11 causes a circulation of the water upwardly, which circulation is maintained throughout the entire water cooling system. The water in the lower part of the casing has a tendency to draw up through the narrow space 44, and through the opening 45.

The heat in the intake and exhaust passages radiates through the walls 25 and 39, and is carried off by the movement of the water. This is specially true of the wall of the exhaust conduit, through which the hot gases are constantly passing, when the engine is in operation. There is also some radiation through the walls 24 and 38 and valve-stem mountings thereof.

The size of the passages 22 and 36 is such as to give thereto approximately the same capacity as that of the valves at the inner ends thereof. In practice the passage 44 could probably be considerably narrowed, and the size of the conduits increased, until they would occupy practically one half of the circumference of the casing 11. The valve-openings could thereby be proportionately enlarged, so that each one thereof

would have a diameter approximating one-half the diameter of the casing. It will be obvious that it would be impossible to put two valves of greater size side by side in the 5 end of the casing, and it is only possible to use valves of the size mentioned by projecting the passages therefrom along the side of the casing, so as to encroach as little as possible on the space required for cooling 10 purposes. The combined space in the casing 11 for the intake and exhaust conduits and water-cooling space is augmented by making use of the wall of such casing as a part of the enclosing walls of said conduits. The 15 casing 11 and head 12 thereon, as well as the inside walls of the conduits, and valve-stem mountings, are integrally formed, reducing the cost of production, and adding to the durability and efficiency of said casing.

20 The valve-stems 18 and 33 slide snugly in their mountings, so that there is no danger of any accumulation of sediment upon said stems. The exhaust passage is also sufficiently large to obviate the danger of any 25 of the residuum of combustion from collecting therein to any extent.

The inner wall of the cylinder 10 is provided with a series of annular channels 48, and the piston 13 is fitted at its lower end 30 with an external channel 49, and at its upper end with similar channels 50, the upper one of which is preferably provided with small perforations extending into the rear wall thereof. In the downward movement 35 of the piston 13 the lower end of the piston projects below the end of the cylinder 10, and into the oil-spray chamber of the engine, carrying with it on its return a portion of the oil, which is fed to the lower channels 48 of the cylinder. The upper channels 50 move downwardly a sufficient distance to receive a supply of the oil from the lower channels 48 and distribute the same to the channels farther up. By this means an oil 40 film is maintained at all times between the inner wall of the cylinder 10 and outer wall of the piston 13. The oil also passes over the upper end of the piston and forms a film between the same and the wall of the casing 45 11. A double seal of oil is thus formed on the opposite walls of the piston, preventing the escape of any of the combustion gases around the end of the piston. The entrance 50 of the oil into the space in the lower end of the piston is prevented by packing rings 51 on the casing 11, near the lower end thereof. These rings also assist in preventing the escape of the gases from the piston on the outside of the casing.

60 The operation of the engine is substantially the same as that of any four-cycle engine. The valve 19 is opened to admit an explosive charge to the space between the casing 11 and piston head 14, and said valve again closed. The charge is then com-

pressed, and ignited, forcing the piston downwardly. The valve 34 then opens, permitting the escape of the exhaust gases, which are driven out by the return movement of the piston.

On account of the water-space within the casing 11 extending to the lower end thereof, the tendency of the lower end of such casing, and the rings 51 thereon, expanding from the heat produced by the successive 70 explosions immediately beneath the same, is overcome, and there is no danger of said rings acquiring too close a contact with the wall of the piston. In fact, the only part 75 that does expand is the piston itself, so that its action will at all times be free from said rings. When the engine is not in operation, a sufficient space is provided between the outer wall of the piston and the inner wall 80 of the cylinder to permit a reasonable amount of expansion of said piston, which will be chiefly at the lower end thereof.

The invention is not limited to the uses herein set forth, but can be adapted for use 85 with other types of engines, and compression devices.

What I claim, and desire to secure by Letters Patent, is:

1. A device of the class described, comprising a cylinder; a cylindrical casing secured in one end thereof and spaced apart therefrom, provided with intake and exhaust conduits having openings in opposite 95 ends of said casing, said casing forming a water compartment about said conduits; valves closing the inner ends of said conduits, and means for suitably opening and closing said valves; a piston operable in the space between said cylinder and casing; and oil-obstructing means on the inner end of 100 the outer wall of said casing.

2. A device of the class described, comprising a cylinder; a cylindrical casing secured in one end thereof, and spaced apart therefrom, provided with intake and exhaust conduits having openings in opposite 110 ends of said casing, following the wall of the casing, and inwardly diverted at their inner ends; valves closing the inner ends of said conduits, and means for suitably opening and closing the same; a piston operable in the space between said cylinder and said casing; means for forming an oil seal on opposite faces of said piston; and rings on the inner end of said casing, to prevent passage of oil inwardly or leakage 115 of gas outwardly through said piston.

3. A device of the class described, comprising a cylinder, provided in its inner face with a series of oil-distributing channels; a cylindrical casing supported in one end thereof, and spaced apart therefrom, containing intake and exhaust conduits; valves closing the inner ends of said conduits, and means for suitably opening and closing said 125 130

valves; and a piston operable in the space between said cylinder and casing, and provided on its outer face with one or more oil distributing channels cooperating with 5 said first-named channels.

4. A device of the class described, comprising an engine cylinder; a cylindrical casing secured in one end thereof, and provided with spaced apart intake and exhaust conduits having openings in opposite ends of said casing, and following the walls thereof, said casing forming a water compartment about said conduits, the space between such conduits forming an upward passage 10 for the water, when heated; valves for the inner ends of said conduits; means for suitably opening and closing said valves; a piston operable in the space between said cylinder and casing; and means for forming 15 an oil seal about said piston to prevent leakage of gas around the same.

5. A device of the class described, comprising a cylinder provided in its inner wall with a series of annular channels; a cylindrical casing secured in one end of said cylinder and spaced apart therefrom, said casing forming a water compartment surrounding said conduits, and having means of communication with the water 20 cooling system of said cylinder; valves closing the inner ends of said conduits, and means for suitably actuating said valves; and a piston operable in the space between said cylinder and said casing, provided on 25 its outer wall with annular channels adapted to cooperate with the first named channels in distributing a film of oil upon said piston.

6. In an internal combustion engine of 40 the class described, a valve supporting member comprising a cylindrical casing, having companion intake and exhaust conduits occupying approximately one-half of the circumferential space in said casing, the wall 45 of said casing forming one of the walls of each of said conduits, and a valve-stem mountings formed integrally with the inner walls of said conduits.

7. In an internal combustion engine of 50 the class described, a valve-supporting member comprising a cylindrical casing containing companion spaced-apart intake and exhaust conduits of substantially tri-angular formation, occupying approximately one-half of the circumferential space in said casing, and provided at their inner ends 55 with valve-openings off-set from the main passages of said conduits; the wall of said casing forming one wall of each of said conduits, and the other two walls of each thereof being exposed to heat-modifying elements contained within said casing.

8. In an internal combustion engine of 60 the class mentioned, a valve-supporting member comprising a cylindrical casing

provided with longitudinal partitions dividing said casing into a compartment for the circulation of heat modifying elements, and a pair of similar conduits with a narrow space between, provided at one end 70 with valve-openings centered on a diametrical line of said casing, the ends of said conduits being off-set to conform to the position of said openings, said conduits being disposed along the wall of said casing at 75 one side of said diametrical line.

9. In an internal combustion engine of 80 the class mentioned, a valve-supporting member comprising a cylindrical casing containing a pair of conduits with a narrow space between, ending at one end in valve-openings centered on a diametrical line of said casing; and a head for said casing, provided with ports in communication with said conduits, said casing, the walls 85 of said conduit, and said head being integrally formed.

10. In an internal combustion engine of 90 the class mentioned, a valve supporting member comprising a cylindrical casing 95 containing companion intake and exhaust conduits of a triangular formation, disposed on one side of a diametrical line of said casing, and provided at one end with valve openings centered on said diametrical line, said conduits being directed inwardly at their ends to conform thereto, and the wall of said casing forming one of the walls of each of said conduits; and a head for said casing, provided with ports in communication with said conduits, said casing and the head thereof, and the inner walls 100 of said conduits being integrally formed.

11. In an internal combustion engine, of 105 the class mentioned, a valve-supporting member comprising a cylindrical casing containing spaced apart intake and exhaust conduits provided with valve openings at one of their ends, said valve openings being centered on a line bisecting the 110 circumference of said casing, and the conduits disposed at one side of said line, and diverted across said line at their ends, so as to coincide with said openings; a pair of valve-stem mountings centered on said line 115 adjacent to the inner walls of said conduits; and a head for said casing, provided with ports in communication with said conduits, said casing and the head thereof, said conduits, and the valve-stem mountings all 120 being integrally formed.

12. In an internal combustion engine of 125 the class described, a valve-supporting member comprising a cylindrical casing containing a pair of spaced-apart conduits occupying substantially one-half of the circumferential space in said casing, and provided at their inner ends with valve openings at a central point in the end of said casing, the ends of said conduits being diverted 130

- toward such central point to permit a valve area of said openings commensurate with the capacity of said conduits; valve-stem mountings adjacent to said conduits and 5 concentric with said valve openings; a spark-plug housing in said casing, in the part thereof opposite to said conduits; and a hollow head for said casing, having ports in communication with said conduits, the 10 space not occupied in said casing and head by said conduits, valve-stem mountings and spark-plug housing being designed for a quantity of heat modifying elements, in circulation.
- 15 13. In an internal combustion engine, in combination with a cylinder, and a piston adapted to reciprocate therein, a cylindri-
- cal casing attached to one end of said cylinder, so as to project into said piston, and containing an intake conduit and exhaust 20 conduit, spaced from each other, and occupying substantially one half of the circumferential area of said casing; and valves in the inner ends of said conduits, each of said valves having a diameter approximating one 25 half of the diameter of said casing, the capacity of said conduits and the valves thereof being substantially the same, and the inner ends of the conduits being diverted in the direction of said valves, so that such 30 capacity may be maintained throughout.

In testimony whereof I affix my signature.

ANTHONY J. METZ.
